HANDLE FOR A PLUMBING FITTING

Joseph William Owings, Jeffersonville, Ind., assignor to
American Standard Inc., New York, N.Y.

Filed Sept. 3, 1970, Ser. No. 24,820

Term of patent 14 years

Int. Cl. D23—01

U.S. Cl. D23—29

FIG. 1

FIG. 2

FIG. 4

FIG. 3

FIG. 5

FIG. 6

FIG. 1 is a perspective view of a handle for a plumbing fitting embodying my new design;

FIG. 2 is an exploded perspective view thereof;

FIG. 3 is a side elevational view thereof;

FIG. 4 is a top plan view thereof;

FIG. 5 is a rear elevational view thereof; and

FIG. 6 is a front elevational view thereof.

I claim:

The ornamental design for a handle for a plumbing fitting, substantially as shown.
